UNITED STATES PATENT OFFICE.

HORACE G. BIRD, OF CHICAGO, ILLINOIS.

AXLE-BOX.

SPECIFICATION forming part of Letters Patent No. 392,845, dated November 13, 1888.

Application filed June 25, 1888. Serial No. 273,073. (No model.)

To all whom it may concern:

Be it known that I, HORACE G. BIRD, a citizen of the United States, residing at Chicago, in the county of Cook and State of Illinois, 3 have invented a new and useful Improvement in Journal-Boxes, of which the following is a specification.

My invention relates particularly to improvement in the class of journal-boxes in 10 which the lower portion forming the oil-receptacle is adjustable upon and separable from the upper portion.

The objects of my improvement are principally to provide a construction of journal-box 15 for use especially on street-cars which shall permit thorough cleansing of its interior readily and without inconvenience and permit ready access to the oil-feeders and springs for holding them in position; to provide more effective means than have hitherto been provided for shielding the interior of the box against the ingress of injurious matter—such as dust and cinders; to provide an improved construction of bearing or “brass,” as it is 20 termed, whereby it shall afford a stop against longitudinal movement of the journal and which shall be readily removable and as readily adjustable in its position, and to provide a generally improved construction of journal- 25 box.

In the drawings, Figure 1 is an end elevation of my improved journal box shown as applied to a car; Fig. 2, a partly-broken transverse section of the same; Fig. 3, a section taken 30 on the line 3 3 of Fig. 1 and viewed in the direction of the arrows; and Fig. 4, a section taken on the line 4 4 of Fig. 1 and viewed in the direction of the arrows.

A, Fig. 1, denotes the bottom sill of a car, 40 from which extend downward the parallel vertical bolts r and r' through opposite ends of the bent brace q and through the adjacent ends of the braces q' , nuts q^2 being provided on the lower projecting ends of the bolts for 45 the usual purpose, and sleeves or hollow columns p surround the bolts and are confined between the under side of a plate, x , on the car-sill and the braces q' , as shown.

B is the journal-box, formed without an integral bottom and provided with lateral sockets o , through which the bolts r and columns p extend, and confined between the sockets o

and plate x are spiral springs n , surrounding the columns.

The construction, as thus described, except 55 as to the bottomless portion of the journal-box, involves no features of especial novelty, but resembles that in common use with journal-boxes of old construction.

The journal-box B is formed in two sections, C and C', the former being like or substantially like any ordinary journal-box, except that it has no bottom, while the latter is in the form of a coverless receptacle, the sides of which fit inside those of the part C, as 60 shown, one end being provided in its upper edge with a semicircular recess to form, with the circular portion of the opening in the corresponding end of the part C, the circular opening through which the journal D enters 70 the box, and the part C' is provided with lateral flanges or ears m , extending from its base portion, and with seats m' , which abut against the lower edges of the part C, extending the full length of the latter. The ears m are perforated and receive the threaded ends of a U-shaped bolt, l , which passes transversely over the part C near its center, the projecting ends of the bolt being provided with nuts l' , which serve to fasten the bolt in place and to secure 75 the part C' to the part C.

Between the inner end of the part C of the sectional journal-box and the adjacent end of the part C' or receptacle for the lubricating material is a recess, k , to receive a ring, E, 85 preferably of felt, surrounding the journal and serving as the outer shield against the ingress of dust and other objectionable matter to the interior of the box, and besides the shield E, I also provide an inner shield, E', like it, and 90 confined in a recess, i , in the part C, and a space, i' , between one inner side of the part C' and a partition, h , extending from the base thereof.

Though it is not new to provide a shield, E, 95 for the purpose named, a single barrier of the kind is found to be inadequate for the purpose for which it is intended, while the double barrier affords effectual protection against the access of dust and the like to the journal.

The inner surface of the upper side of the part C is recessed, as shown at g , and an opening, s , controlled by a screw-plug, s' , leads into the recess and affords a duct for oiling the

brass, hereinafter described, and to which the recess g leads, as shown, and at opposite ends of the recess g are offsets g' and g'' , between which the bearing or brass F fits, and is confined against longitudinal movement, while lateral movement thereof is prevented by its confinement between lugs f , provided on the inner sides of the part C.

The brass F, which is hollowed out longitudinally on its upper side, as shown, is recessed on its under side near its forward end, as shown at e , the recess fitting over the collar e' on the end of the journal when the box is in position, whereby a stop is provided to prevent longitudinal play of the journal, which would tend to produce wear thereon and permit the introduction of dust and the like past the inner shield, E', into the journal-box.

G G are the lubricating-strips, composed, preferably, of stiff fibrous material in flat strips held together by opposing springs, d, extending against them from opposite corners of the base or side of the part C'.

The strips G are spread apart along their upper edges by the insertion between them of the journal D, and serve to carry to the latter, by capillary attraction, the lubricant contained in the receptacle C'.

The outer end of the journal-box is provided with a hole, c, through which access is gained to the interior, and which is provided with a removable cover, c'.

To clean the box or gain access to the interior thereof for any of the purposes stated, the brace q is first removed by loosening one nut, q'' , and turning the brace on its other fastened end, and then the nuts l' are loosened, permitting removal of the part C', which contains the supply of lubricating material of which the box is to be cleansed, and after cleansing the part is readjusted in its position and secured by applying the nuts, when the brace q is again secured in place. To remove the brass F, the box B is pried to raise the shoulder or offset g'' from engagement with the head of the brass, when the latter may be withdrawn through the opening c, the cover c' being previously removed, thus obviating the necessity of raising the car, as required with all other journal-boxes, and the insertion of a new brass is effected by introducing

it into position through the opening c with the box raised, as described, by prying.

What I claim as new, and desire to secure by Letters Patent, is—

1. A sectional journal-box, B, comprising, in combination, a bottomless part, C, and a part, C', in the form of a coverless receptacle inserted into the part C, and provided with perforated ears m , extending laterally from its base portion, and with seats m' , abutting against the lower edge of the part C, a U-shaped bolt, l, straddling the part C and extending at its ends through the ears m and nuts l' on the ends of the bolt, substantially as described. 60

2. In a sectional journal-box, the combination of a bottomless part, C, having recesses k and i near the opening, through which the journal is admitted, a part, C', in the form of a receptacle, removably secured to the part C, 70 and forming the base thereof, a partition, h, extending upward from the bottom of the part C', and shields E and E', confined in the said recesses and to surround the journal, substantially as and for the purpose set forth. 75

3. In combination, a journal-box having an opening, c, and provided internally with a recess, g, having a controllable oil-duct, s, and with offsets g' and g'' and lugs f , a journal, D, having a collar, e' , near its end, and a brass, 80 F, hollowed on its upper side and fitting between the said offsets and provided on its under side near the outer end with a recess, e, fitting over the collar e' , substantially as and for the purpose set forth. 85

4. A sectional journal-box comprising, in combination, a bottomless part, C, having recesses k and i near the opening through which the journal is admitted, a brass, F, confined against play in the part C and affording a 90 stop to longitudinal movement of the journal, a part, C', in the form of a receptacle removably secured to the part C and forming the base thereof, a partition extending upward from the bottom of the part C', annular shields E 95 and E', confined in the recesses k and i and to surround the journal, and a covered opening, c, in the box, substantially as described. 95
